UNITED STATES PATENT OFFICE

131,911

DESIGN FOR A LITURGICAL ORPHREY OR SIMILAR ARTICLE

Apollinaris Baumgartner, New York, N. Y.

Application March 12, 1942, Serial No. 106,161

Term of patent 3½ years

To all whom it may concern:

Be it known that I, Apollinaris Baumgartner, a citizen of the United States, residing in the city, county, and State of New York, have invented a new, original, and ornamental Design for a Liturgical Orphrey or Similar Article, of which the following is a specification, reference being had to the accompanying drawing, forming a part thereof.

The figure of the drawing is a plan view of a liturgical orphrey or similar article, showing my new design.

I claim:

The ornamental design for a liturgical orphrey or similar article, as shown.

APOLLINARIS BAUMGARTNER.
